UNITED STATES PATENT OFFICE.

WALTER WARREN STEARNS, OF BUFFALO, NEW YORK.

PACKING APPARATUS.

Application filed June 2, 1923. Serial No. 643,094.

To all whom it may concern:

Be it known that I, WALTER W. STEARNS, a citizen of the United States, residing at Buffalo, in the county of Erie and State of New York, have invented certain new and useful Improvements in Packing Apparatus, of which the following is a specification, reference being had therein to the accompanying drawing.

10 This invention relates to packing apparatus and more particularly to that type of apparatus in which a vacuum producing means is associated directly with a container and in which the cover or closure member 15 of the container is enclosed within a portion of the packing apparatus and acts as a check-valve to permit egress of air from the container and prevent ingress of air thereto. 20 Heretofore in devices of this character the apparatus was designed to operate in conjunction with special types of containers or was made to enclose the entire container, in which latter instance it was necessary to 25 first place the container in the receptacle and then attach the exhausting pump to the receptacle. The disadvantages of this type of device are obvious and require no discussion. The first type of device requiring 30 a particular type of container made it necessary, if the packing apparatus were to be used, to purchase an entire new equipment of containers, which made the use of the packing apparatus almost prohibitive. 35 It is therefore the principal objects of this invention to avoid the difficulties which have been encountered in the promotion of devices of the types mentioned, and to provide a device which is applicable to any type 40 of ordinary preserving jar.

A further object of the invention is the production of a cheap and efficient device for exhausting air from ordinary packing containers such as the glass jars commonly 45 in use in households for preserving articles of food, and also to provide a device which not only can be applied to any type of preserving jar now on the market, but which is conveniently applied and operated, and 50 requires no special course of instruction in its use.

A still further object of the invention is to provide a vacuum packing apparatus for use on domestic preserving receptacles 55 wherein means is provided for conveniently

adjusting the tension applied to the cover or closure member of the container, and to provide safety means by which the amount of vacuum produced within the container may be regulated to prevent rupture of said 60 container.

Further objects of the invention will appear as the following specific description is read in connection with the accompanying drawing which forms a part of this application, and in which—

Figure 1 is an elevation of the device on a reduced scale and showing a modified type of plunger handle;

Figure 2 is a detail vertical sectional view 70 on an enlarged scale and showing the preferred type of handle to be employed; and

Figure 3 is a horizontal sectional view taken on the line 3—3 of Figure 2.

Referring now to the drawing I have 75 illustrated, for the purpose of showing the operation of this device, an ordinary domestic preserving jar of the "Atlas" type. This container is illustrated generally at 1 and is provided as is usual, with a reduced 80 neck 2 forming a shoulder 3 which merges the neck gradually into the body of the container. The jar is sealed by a cap or closure member 4 which rests upon a packing gasket 5 usually of rubber. All of the foregoing parts are parts of the ordinary 85 "Atlas" type of jar and generally embody features found in all domestic preserving receptacles.

The packing apparatus which co-acts with 90 the container comprises a hood 6 of cylindrical form in general outline, open at its lower end and closed at its upper end by an integral top piece 7 which supports the pump barrel 8 rising perpendicularly therefrom.

Projecting from the lower end of the hood 6 is an annular packing gasket 9 of any suitable material, but preferably of soft and comparatively resilient rubber which is held 100 in place by a clamping band 10 of any preferred construction. This packing gasket 9 when the device is applied to the container is adapted to rest upon and fit the shoulder 3 snugly so as to prevent the ingress of any 105 air at this point, and being of very flexible material will conform to any inaccuracies in the container.

At intervals throughout the height of the hood I provide upon opposite sides thereof 110

a plurality of grooves 11 extending in parallel lines and separated vertically, and at their terminal ends by a smooth portion 12. These grooves are arranged in pairs, 5 one upon either side of the inner face of the hood, and are arranged to receive the terminal hooked ends 13 of a bridge piece 14, which is arched downwardly as shown, and has depending from its longitudinal center 10 a light spiral spring 15 adapted to bear upon the center of the closure member 4 whereby said closure member will be held firmly seated against the gasket 5, but which permits free upward movement of said closure member to unseat it from the gasket 5 when a predetermined quantity of air has been exhausted from the hood 6 as will be hereinafter described.

By turning the bridge piece 14 so as to 20 relieve the hooked ends thereof from the opposite grooves 11 and so they will ride upon the smooth portions 12 the bridge piece 14 may be raised or lowered in the hood to accommodate the same to preserving jars 25 having varying neck lengths, and thereby insure proper contact of the spring in each instance with the closure member 4.

The pump barrel 8 is closed at its upper end by a centrally apertured cap 16 and 30 sliding through the aperture in the cap is a piston rod 17 preferably having its handle formed as an integral part thereof and in the manner shown at 18, so as to limit its downward movement and thus prevent injury to the operator's fingers. The handle, 35 however, may be constructed as shown at 19 in Figure 1 if desired. The lower end of the piston rod has secured thereon by means of a nut 20 the piston which, as shown, is constructed of a packing cup 21 disposed between the disks 22 and 23. The former being of somewhat smaller diameter than the latter so as to receive the flanges of the packing cup between its periphery and the inner 40 walls of the pump barrel.

The disks 22 and 23, and the packing cup 21 are provided with aligned ports 24 for the passage of air, and these ports are closed 50 upon the upper side of the piston by a check-valve 25 which is in the form of a flexible disk surrounding the piston rod 17 and limited in its upward movement by projections 26 struck up from the piston rod in a well known manner.

Within the confines of the pump barrel 55 the cap piece 7 of the hood 6 is provided with a plurality of apertures 27 and seated upon the upper surface of the cap piece is a rubber or other suitable packing gasket 28 having corresponding apertures 29 arranged 60 therein. Seated upon this gasket is an imperforate disk 30 having an integral stem 31 threaded at its lower end to receive an adjusting nut 32. Arranged between the nut 65 and the bottom of the cap piece 7 is a spiral

spring 33 which acts normally to hold the disk seated against the gasket 28 and to prevent any ingress of air into the hood upon the down-stroke of the piston, but permitting the elevation of the disk 30 upon the up-stroke of the piston so as to exhaust air from the hood.

In the operation of the device the hood is placed over the neck of the vessel, the hood being of sufficient size to encompass the neck of any ordinary domestic preserving container, and the gasket 9 pressed firmly into engagement with the shoulder 3 on the body of the receptacle. At this time if the bridge piece 14 is properly adjusted the spring 15 will engage the closure member 4 and hold the same seated against the gasket 5 so as to prevent any ingress of air into the receptacle 1. The operator then manipulates the pump while holding the hood firmly in position, the up-stroke of the piston exhausting air from the hood and from the receptacle. Repeated strokes of the pump will exhaust the air from the receptacle to the required degree when the hood may be lifted from the receptacle.

After the hood has been raised from the receptacle the atmospheric pressure is sufficient to firmly hold the closure member in position upon the gasket and to prevent any ingress of air into the container. This, of course, being due to the sub-atmospheric pressure within the container.

In order that the operator may determine accurately how much air to exhaust from the receptacle, and in order to conveniently destroy the vacuum within the hood so that it may be removed from the container without effort on the part of the operator, I provide a combined safety and relief valve 100 which is located to one side of the pump barrel on the cap piece 7. This valve comprises a shank 34 externally threaded upon its upper end to receive an internally threaded adjusting nut 35. Between this nut and the cap piece is located a spiral spring 36 which normally holds the head of the bolt 37 with its interposed packing gasket 38 firmly against the underside of the cap piece 105 so as to close the opening through which the shank passes, and which opening is somewhat larger than the shank to permit free ingress of air when the head is lowered by a force of atmospheric pressure or by the operator pressing downwardly upon the nut 35.

By adjusting the nut 35 upon the shank 30 the tension of the spring may be regulated so that the valve will open at any desirable pressure thereby automatically regulating the amount of vacuum produced in the container 1. After the required amount of vacuum has been established and if at this time the safety valve has not operated, downward pressure upon the nut 35 will unseat the gasket 38 and permit ingress of 110 115 120 125 130

air to destroy the vacuum in the hood 6. When this is done the hood may be removed from the container without effort.

If desirable I may place upon the cap 5 piece 7 a suitable vacuum gage so that at all times the operator may readily ascertain the sub-atmospheric pressure in the container.

It will be noted from an inspection of the drawing that I have formed adjacent the 10 base of the hood, an annular external rib against which the upper edge of the gasket 9 is adapted to abut, so that any vertical movement of this gasket, due to pressure exerted upon the hood in applying the de- 15 vice, is prevented.

The bridge piece 14 is preferably made of resilient material so that its hooked ends 13 will at all times be held firmly in the grooves, and yet may be readily removed 20 therefrom when it is desired to change the adjustment of the same.

I claim:—

1. In a vacuum packing apparatus, for use 25 with a container having a neck and a single mouth, and a closure member for the mouth freely closing the same, of a hood adapted to enclose the neck and form an air-tight joint with said container, means adjustably attached to said hood for normally holding 30 the closure member seated, and means connected to the hood for exhausting air from the container.

2. In a vacuum packing apparatus, for use 35 with a container having a neck and a single mouth, and a closure member for the mouth freely closing the same, of a hood adapted to enclose the neck and form an air-tight joint with said container, means carried adjustably by said hood for normally holding 40 the closure member seated, and means carried by the hood for exhausting air from the container.

3. In a vacuum packing apparatus, for use 45 with a container having a neck and a shoulder below the neck, together with a closure for the mouth of the container, of air exhausting mechanism embodying in part a pump and a hood adapted to enclose the neck of the container and to form an air-tight joint with the shoulder, and means adjustably carried by the hood for normally holding the closure member seated.

4. In a vacuum packing apparatus, the 55 combination of a member adapted to form an air-tight connection with a container from which air is to be exhausted, a pump associated with said member, and an adjustable spring seated valve for automatically regulating the amount of air exhausted 60 from the container together with means carried by said member for holding a closure member seated on the container.

5. In a vacuum packing apparatus, the 65 combination of a member adapted to form an air-tight connection with a container

from which air is to be exhausted, a pump associated with said member, and adjustable means for determining the amount of air exhausted from the container together with means carried by said member for holding 70 a closure member seated on the container.

6. In a vacuum packing apparatus, for use with a container having a freely seated closure member, of a hood adapted to form an air-tight connection with said container, 75 a pump associated with the hood for exhausting air therefrom and from the container, and a safety valve carried by the hood and adapted to regulate the amount of air exhausted from the container together 80 with means carried by the hood body for holding said closure member seated upon the container.

7. In a vacuum packing apparatus, for use 85 with a container having a freely seated closure member, of a hood adapted to form an air-tight connection with said container, a pump associated with the hood for exhausting air therefrom and from the container, and an adjustable safety valve carried by 90 the hood and adapted to automatically regulate the amount of air exhausted from the container, said valve adapted to be manually actuated for breaking the vacuum in the hood together with means carried by the 95 hood body for holding said closure member seated upon the container.

8. In vacuum packing apparatus, for use 100 with a container having a shouldered body and a reduced neck and a freely seated closure member closing the mouth of the container and resting upon a sealing gasket, of a rigid hood adapted to surround the neck of the container and to form an air-tight joint with said shoulder, air exhausting apparatus carried by said hood and means adjustably carried by the hood body for normally holding said closure member seated.

9. In a vacuum packing apparatus, a hood 110 adapted to form an air-tight connection with a receptacle having a free cover or closure member, a bridge piece adjustably and removably mounted in the hood and a resilient member interposed between the bridge-piece and the closure member for holding the latter seated upon the receptacle.

10. In a vacuum packing apparatus, a hood adapted to form an air-tight connection with a receptacle having a free closure member, a resilient bridge piece adjustably and removably mounted within the hood and a spring depending from the bridge piece and adapted to normally retain the closure member in position upon the receptacle.

11. In a vacuum packing apparatus, a hood having a plurality of internal and longitudinally spaced grooves, said hood adapted to form an air-tight joint with a receptacle having a freely movable closure member, a bridge piece adjustably engaged 130

- in said grooves and resilient means interposed between the bridge piece and the closure member for normally holding the latter seated upon the receptacle.
- 5 12. In a packing apparatus, a hood adapted to form an air-tight joint with a receptacle having a free closure member, said hood being provided with longitudinally spaced and transversely separated internal
10 grooves, a resilient bridge piece having hooked ends adapted to be adjustably en-
- gaged with any of said grooves and a spring carried by and depending from the bridge piece and adapted to normally retain the closure member seated upon the receptacle. 15
- In testimony whereof I affix my signature in the presence of two witnesses.
